CLAIM

The ornamental design for an electric skateboard, as shown and described.

DESCRIPTION

FIG. 1 is a perspective view of an electric skateboard showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of area “9” in FIG. 2.

The evenly spaced broken lines denote portions of the electric skateboard that form no part of the claimed design. The dash-dot broken lines shown in FIGS. 2 and 9 are for the purpose of indicating the enlarged partial views and form no part of the claimed design.
